UNITED STATES PATENT OFFICE

REUBEN N. TRANE, OF LA CROSSE, WISCONSIN

RADIATOR

Application filed May 31, 1930. Serial No. 458,113.

My invention relates to an air fin type radiator wherein a multiplicity of thin and fragile metallic fins are mounted upon thin and fragile metallic heat tubes and supporting side and cross plates interposed to form a substantial independent structure which will supply a supporting and protective frame for the radiator. In the past air fin type radiators have been constructed of substantial or heavy material which rendered further support unnecessary.

One of the objects of my invention is the production of an air fin type radiator to be strong enough to support additional weight and which is strong enough to withstand abuse and rough handling and at the same time prevent undue air leakage.

Another object of my invention is a radiator with a supporting frame which will allow a free expansion of the radiator at different temperatures.

The novel features of my invention are fully described in the following specification:

Fig. 1 is a top view of an air fin type radiator.

Fig. 2 is a side elevation of an air fin type radiator.

Fig. 3 is a top view of one of the supporting plates.

Fig. 4 is a side view of one of the supporting plates.

Fig. 5 is a top view of side plate and cross plate structure independent of the tubes and fins.

Referring to Fig. 1, the thin walled metallic fins 10 are mounted upon thin walled metallic heat tubes 11. The heat tubes 11 are connected into headers 12 through which flows the source of heat. The side plates 13 are made of steel or other metal strong enough to withstand pressure and weight load and extend the entire length of the heater occupied by the fins. To allow expansion and contraction of the heating radiator without

influence of the side plates 13, the side plates 13 are not attached to the headers 12, but the side plates 13 are supported by a cross supporting member 14 composed of a sheet of metal substantially the same size as the extended fin 10 but of much greater strength

and called cross plates. The supporting plate 14 is equipped with flanges 15 on either end of the plate and with the apertures 16 through which the heat tubes 11 pass. The middle cross plate is designated as 14 and the end 55 cross plates as 14'.

The cross plate 14 is mounted on the heat tubes having close contact, but not close enough to restrict or prevent movement of the tubes through the cross plates and not 60 necessarily as close a contact as the fins have with the heat tubes 11. The cross plate 14 is attached to the side plates 13 at 19 by electric spot welding or by other suitable means. The cross plate 14 is mounted upon the heat 65 tubes 11 in a plane parallel to the flow of air through the heater and at substantially a right angle to the side supporting plates 13 to allow a free passage of air.

The cross plates 14 and the side plates 13 70 form a supporting structure which is mounted on the heat tubes 11, and the cross plates 14 are mounted on the heat tubes 11 close to the headers 12. It is apparent that if the cross plates are mounted on the tubes 11 close to the headers 12, that the tubes 11 at a point close to the headers would support a much greater load and strain through the medium of the cross plates than were the cross plates mounted at a much farther distance from the headers. 75

The side plates 13 are also spaced from the edges of the fins 10 so that with any movement of the fins, the fins will not touch the side plates 13 so as to prevent an objectionable scraping noise upon expansion of the heater. 80 The metallic fins 10 are of thin metallic substance approximately 5/1000 to 20/1000 of an inch in thickness, and the tubes 11 are thin walled metal tubes of a thickness ranging from 20/1000 to 35/1000 of an inch in thickness. 85

It is apparent in a structure such as this that instead of headers, U bends in the ends of the tubes can be used as well as headers. In operation the flow of the air will be 95 through the heater in the direction of the arrow 17 and will be in a manner similar to a convection type heater.

It is apparent, therefore, from this that there is a combined structure of the side 100

plates 13 and the supporting plates 14 which are mounted upon the heat tubes 11 and form a supporting ladder independent of the headers, which gives a great strength to the entire heating radiator to such an extent that it is possible for a person to stand upon this radiator and not bend it, notwithstanding the fact that the heat tubes 11 and the fins 10 are composed of thin metallic walls.

- 5 10 There is a space 18 between the cross plate 14 and the header 12 and the space 20 between the cross plate 14 and the fin 10 so that upon expansion of the tubes longitudinally due to increase of temperature and the 15 difference in the amount of change of temperature between the tubes 11 and the side plates 13, that there is a freedom of motion of the heat tube 11 through the cross plate 14 without causing tension between the supporting 20 frame and the radiator proper. When in use there is especially in six foot radiators a considerable difference in expansion between the tubes 11 and the side plates 13, due to differences in temperature and the 25 difference in co-efficients of expansion in the different metals.

While I have shown my invention as embodied in the specific form shown and described and have suggested only the specific 30 alternative, I contemplate that many changes may be made without departing from the scope or spirit of my invention.

I claim:

1. An air fin type radiator, in combination, a multiplicity of thin metal fins mounted on a multiplicity of thin walled metal heat tubes connected into opposite headers, stiff metal side plates, the side plates being spaced from the edge of said fins, in planes at 40 an angle to the planes of the fins and spaced from each other and secured to each other by cross plates mounted on the heat tubes to form a protective frame for the radiator, the cross plates being flanged and secured 45 to the side plates by means of said flanges.

2. An air fin type radiator, in combination, a multiplicity of thin metal fins mounted on a multiplicity of thin walled metal heat tubes connected into opposite headers, 50 stiff metal side plates in planes at an angle to the planes of the fins and spaced from each other and secured to each other by cross plates mounted on the heat tubes to form a protective frame for the radiator, the cross 55 plates being flanged and secured to the side plates by means of said flanges, being independent of the headers, the side plates being spaced from the edge of said fins.

3. An air fin type radiator, in combination, a multiplicity of thin metal fins mounted on a multiplicity of thin walled metal heat tubes connected into opposite headers, a supporting frame comprising stiff side plates spaced from the edge of the fins and 60 from each other and secured to each other 65

by stiff metal cross plates mounted on the heat tubes, the side plates being unattached to the headers.

4. An air fin type radiator, in combination, a multiplicity of thin metal fins mounted on a multiplicity of thin walled metal heat tubes, connected into opposite headers, an independent supporting frame comprising stiff metal side plates attached to stiff metal cross plates mounted on the heat tubes 70 close to the headers but independent of the headers, with sufficient clearances to allow the free expansion and contraction of the heat tube through the cross plates when there is a difference in temperature between the supporting frame and the heat tubes.

5. An air fin type radiator, in combination, a multiplicity of thin metal fins mounted on a multiplicity of thin walled metal heat tubes connected into opposite headers, 85 stiff metal side plates in planes at an angle to the planes of the fins and spaced from each other and secured to each other by cross plates mounted on the heat tubes, at least one of said cross plates being spaced from 90 said headers and intermediate thereof to form a supporting frame for the radiator to prevent bending of said heat tubes.

6. An air fin type radiator, in combination, a multiplicity of thin metal fins mounted on a multiplicity of thin walled metal heat tubes connected into opposite headers, stiff metal side plates parallel to each other and to the heat tubes and at right angles to the fins, the side plates secured to each other 100 by cross plates, apertures in the cross plates and heat tubes passing through said apertures, one of said cross plates being mounted on said heat tubes intermediate the said headers to prevent bending of said heat tubes.

7. An air fin type radiator, in combination, a multiplicity of thin metal fins mounted on a multiplicity of thin walled metal heat tubes connected into opposite headers, stiff metal side plates parallel to each other and to the heat tubes and at right angles to the fins, the side plates being independent of the headers, secured to each other by cross plates, 110 apertures in the cross plates and heat tubes passing through said apertures, one of said cross plates being mounted between said fins and on said heat tubes to prevent said heat tubes from sagging.

8. An air fin type radiator, in combination, a multiplicity of thin metal fins mounted on a multiplicity of thin walled metal heat tubes, stiff metal side plates in planes at an angle to the planes of the fins and spaced from each other and secured to each other by flanged cross plates mounted on the heat tubes between said fins, to form a supporting frame for the radiator, preventing said heat tubes from sagging.

9. An air fin type radiator, in combination,

a multiplicity of thin metal fins mounted on a multiplicity of thin walled metal heat tubes connected into opposite headers, a supporting frame comprising stiff side plates spaced 5 from the edge of the fins and from each other and secured to each other by stiff metal cross plates, at least one of said cross plates being mounted laterally on the heat tubes intermediate the said headers, to form a supporting 10 frame for said radiator and to prevent bending of the heat tubes.

10. An interchanger, in combination, a multiplicity of thin metal fins mounted on a multiplicity of thin wall metal heat exchange 15 tubes, stiff metal side plates mounted on said heat exchanger by means of cross plates, said cross plates being slidably mounted on the said heat exchange tubes, at least one of said cross plates being mounted intermediate the 20 end to form a supporting frame for the radiator and prevent sagging of the heat tubes.

In witness whereof, I hereunto subscribe my name this 28 day of May, 1930.
